F. HOOPER

WRENCH

Filed Jan. 25, 1921

Inventor:
Forest Hooper
by Jas. H. Blumherr
atty.

UNITED STATES PATENT OFFICE.

FOREST HOOPER, OF EDMONTON, ALBERTA, CANADA.

WRENCH.

Application filed January 25, 1921. Serial No. 439,892.

To all whom it may concern:

Be it known that I, FOREST HOOPER, a citizen of the United States, residing in Edmonton, Alberta, Canada, have invented an improvement in Wrenches, of which the following description, in connection with the accompanying drawings, is a specification, like characters on the drawings representing like parts.

10 This invention relates to wrenches and has for its object to provide a wrench which can be used as a pipe wrench without danger of crushing the pipe, and also as a monkey wrench which can be used on finished 15 valves, nuts and the like without marring the nickel or other finish.

The invention also has for its object to provide a wrench of the character described, which can be quickly and positively adjusted to any size pipe or fitting within limits.

Provision is made for closing the jaws of the wrench after they have been adjusted to the pipe and to increase the grip of the jaws as they are closed, and further to prevent the 25 jaws from locking on the pipe when the pressure or tension is removed.

These and other features of this invention will be pointed out in the claims at the end of this specification.

30 Fig. 1 is a side elevation of a wrench embodying this invention, showing the same in its open position.

Fig. 2, a like elevation showing the wrench in its closed position on a pipe.

35 Fig. 3, a longitudinal section of the wrench shown in Fig. 1.

Fig. 4, a section on the irregular line 4—4, Fig. 2, and

40 Fig. 5, a section on the line 5—5, Fig. 2. Referring to the drawings *a*, *b*, represent the two jaws of the wrench and *c*, *d*, the shanks thereof.

The jaws *a*, *b*, may be designated the upper and lower jaws, and are provided with 45 substantially flat or straight opposing faces 10, 12, which enable the wrench to be used as a monkey wrench, and said faces are provided between their ends with concavities or recesses 13, 14, which form with the flat 50 faces 10, 12, two relatively sharp corner teeth 15, 16, on each jaw, and the said recesses may also be provided between said corner teeth with additional teeth as shown. The corner teeth 15, 16 afford two separate bearing points on each jaw for engagement with the pipe 20 and thereby avoid the danger of

crushing the pipe, when pressure is applied to turn the same. The corner teeth 15, 16 are flush with the faces 10, 12 of the jaws and therefore do not interfere with the use 60 of the wrench as a monkey wrench, and do not mar the nickel or other finish on valves, nuts and the like when the wrench is used thereon.

The jaws *a*, *b*, in the present instance are 65 both movable, and provision is made for quickly obtaining a coarse adjustment of the jaws and also for a finer adjustment of the same. To this end, the shank *c* of the jaw *a* is inserted into a socket or guideway 70 21 in a handle 22, and is provided on one face with teeth 23 suitably shaped to be engaged by screw or helically arranged external teeth 24 on a rotatable nut or adjusting member 25 which is mounted to turn on 75 a pivot pin 26 between brackets 27, 28, attached to the handle 22. The pivot pin 26 is extended freely through the bracket 27 and nut 25 and is in threaded engagement with the bracket 28. The screw teeth 24 of the 80 adjusting nut 25 project into the socket or guideway 21 and engage teeth 23 on the shank *c* of the upper jaw *a*.

The teeth 24 do not extend completely 85 around the nut 25 but are interrupted by removing a portion thereof so as to provide the nut with a plain or untoothed portion 30 on its outer circumference, which, when turned so as to oppose the teeth 23 on the shank *c*, effects disengagement of the nut from the shank *c* and permits the latter to be slid 90 freely in the guideway or socket 21, thereby enabling the jaws *a*, *b*, to be quickly engaged with the pipe 20 or other object to which the wrench is applied.

95 This engagement of the jaws *a*, *b*, is effected by what may be considered a coarse adjustment of the jaws, and when thus adjusted, a finer adjustment of the outer jaw *a* may be obtained by turning the nut 25 so as 100 to first engage the teeth 24 on the nut with the teeth 23 on the shank *c*, and then on further turning the nut the jaw *a* is moved toward the jaw *b* by the screw teeth 24 on the nut, which latter may be provided with a 105 wing or handle 35 to facilitate turning the same.

Provision is also made for adjusting the 110 jaw *b* with relation to the jaw *a*, and to increase the grip of the jaws on the pipe 20 or other article at the will of the operator. To this end, the jaw *b* is provided with a

strap or guiding member 36 through which the shank *c* of the upper jaw *a* is extended and which serves to guide the lower jaw in its movement and to connect it in operative relation with the upper jaw. The movement of the lower jaw *b* on the shank *c* of the upper jaw is effected by an elbow lever pivotally mounted on the handle 22 and pivotally connected with lower jaw *b*. The elbow lever is preferably made as herein shown and comprises two elbow shaped members 40 located on opposite sides of the handle 22 and a back member 41 connecting the lower ends of said side members and forming therewith a channel shaped handle for the lever which embraces the lower end of the handle 22. The elbow shaped members 40 turn on trunnions or circular projections 42 on the handle 22, see Fig. 4, and are retained on the handle 22 by screws 43. The short arms of the elbow shaped members 40 are pivotally connected with the lower jaw *b* by the pivot pin or screw 44.

The back member 41 cooperates with the handle 22 and the latter acts as a stop to limit the movement of the jaw moving lever 40, and prevents the lever being moved beyond the center on which it turns and thereby prevents the jaws *a*, *b*, becoming locked on the pipe when the pressure on the lever is removed.

In the normal or open position of the wrench, the lever 40 is turned so that its long arm extends away from the handle 22 as shown in Fig. 1, and the bottom of the jaw *b* bears against the bracket 28.

When it is desired to apply the wrench to the pipe 20 or other article, the adjusting nut 25 is turned so that its flat or untoothed portion 30 opposes the teeth 23 on the shank *c*, and when thus positioned the shank *c* can be slid in the guideway 21 so as to bring the jaw *a* substantially into engagement with the work, with which the lower jaw *b* is loosely engaged. The nut 25 is then turned to engage its teeth 24 with the teeth 23 of the shank *c* to effect the final adjustment of the upper jaw *a*. When the parts are thus positioned on the pipe 20 or other work, the operator grasps the handle 22 and lever 40 and exerts pressure on the latter thereby moving the lower jaw *b* into firm engagement with the pipe 20, and when thus engaged the pressure of the lower jaw can be gradually increased by pressure applied to the lever 40 which may be effected as the handle of the wrench is pulled or pressed upon to turn the pipe. By relieving the pressure from the jaw moving lever 40, the jaws are automatically released from the pipe and the wrench can be turned backward to get a new grip when desired or required.

As noted above, the wrench is equally applicable for use as a monkey wrench, with

out danger of marring the finish on the work.

One embodiment of the invention is herein shown, but it is not desired to limit the invention to the particular construction shown.

Claims—

1. In a wrench, in combination, a jaw provided with a substantially smooth gripping face having a recess therein to form corner teeth, a shank attached to said jaw and provided with teeth, a handle having a guideway in which said shank is inserted, a rotatable member provided with external screw teeth for engagement with the teeth on said shank, and provided with an untoothed portion to permit disengagement of said shank from said rotatable member, a cooperating jaw provided with a substantially smooth gripping face having a recess therein to form corner teeth, an elbow lever having its long arm pivoted to said handle and its short arm pivotally connected with said cooperating jaw to move the same, and guiding means attached to said cooperating jaw and engaging said shank.

2. In a wrench, in combination, a handle, a jaw having a shank in sliding engagement with said handle, means for effecting movement of said shank and jaw longitudinally of said handle, a second jaw co-operating with the first-mentioned jaw and provided with a guiding member through which the shank of the first-mentioned jaw is extended and movable, and a lever pivoted to said handle and connected with said second jaw to effect movement of the latter on the movable shank of the first-mentioned jaw.

3. In a wrench, in combination, a handle, a jaw provided with a shank guided by and movable lengthwise of said handle and provided with screw teeth, a rotatable member having external screw teeth for engagement with the teeth on said shank and provided with an untoothed portion to effect disengagement of the said rotatable member from said shank, a second jaw movable toward the first mentioned jaw, and a lever pivoted to said handle for moving said second jaw.

4. In a wrench, in combination, a handle, a jaw provided with a shank having teeth and movable lengthwise of said handle, a second jaw in sliding engagement with said shank and bodily movable toward the first-mentioned jaw, a nut rotatably mounted on said handle and having a mutilated external thread for engagement with and disengagement from the teeth on said shank to permit the jaw to be moved with relation to said handle for coarse adjustment independently of the nut and to permit the jaw to be moved for fine adjustment by a partial rotation of said nut, and means for moving the second jaw toward the first-mentioned jaw with an increasing pressure.

5. In a wrench, in combination, a handle provided with a guideway, a jaw having a shank slideable in said guideway and provided with screw teeth, and a rotatable member

second mentioned jaw to effect movement of the latter by movement of the lever under all conditions.

25

6. In a wrench, in combination, a handle, a jaw having external screw teeth for engagement with the teeth on said shank and provided with an untoothed portion to effect disengagement of the said rotatable member from said shank, a second jaw movable toward the first mentioned jaw, and a lever pivoted to said handle and pivotally connected with said second jaw to move the latter.

7. In a wrench, in combination, a handle, a jaw provided with a shank guided by and movable lengthwise of said handle, a nut carried by said handle and co-operating with said shank to effect movement thereof lengthwise

30

10 of said handle, a second jaw mounted to move on said shank, and an elbow lever having its long arm pivoted to said handle and its short arm pivotally connected with said

lengthwise of said handle, a second jaw mounted to move on said shank, and an elbow lever having its long arm pivoted to said handle and its short arm pivotally connected with said second mentioned jaw to effect movement of the latter by movement of the lever under all conditions, and means on said lever cooperating with said handle to limit the movement of said lever toward said handle.

35

15 20 In a wrench, in combination, a handle, a jaw provided with a shank guided by and movable lengthwise of said handle, a nut carried by said handle and cooperating with said shank to effect movement thereof lengthwise of said handle, a second jaw mounted to move on said shank, and an elbow lever having its long arm pivoted to said handle and its short arm pivotally connected with said

In testimony whereof, I have signed my name to this specification.

40

FOREST HOOPER.
